(57) CLAIM

I claim the ornamental design for a helmet with visor, as shown and described.

DESCRIPTION

FIG. 1 is a front perspective view of a helmet with visor showing my new design, with the visor in a closed position; FIG. 2 is a front perspective view thereof, with the visor in a raised position;

FIG. 3 is a front view thereof, with the visor in a closed position;

FIG. 4 is a front view thereof, with the visor in a raised position;

FIG. 5 is a side perspective view thereof, with the visor in a closed position;

FIG. 6 is a rear view thereof; and,

FIG. 7 is a top view thereof.
